UNITED STATES PATENT OFFICE

FRANCIS ELLSWORTH BUXTON, OF RICHMOND, INDIANA.

ADJUSTABLE JOURNAL-BOX.

No. 895,425.

Specification of Letters Patent. Patented Aug. 11, 1908.

Application filed November 4, 1907. Serial No. 400,444.

To all whom it may concern:

Be it known that I, FRANCIS ELLSWORTH BUXTON, a citizen of the United States, residing in the city of Richmond, in the county of Wayne and State of Indiana, have invented certain new and useful Improvements in Adjustable Journal-Boxes, in addition to that secured to me by Letters Patent of the United States on the 25th day of June, 1907, No. 857,788, and referred to by same title as above.

The following is a full and accurate specification of my present invention, being such as will enable others to make and use the same with absolute exactitude.

The object of my present invention is to provide an adjustable journal-box or bearing which will be strong and durable in construction, neat and attractive in appearance, which will be simple in its several parts and easy to actuate, and which can be manufactured and sold at a comparatively low price.

More specifically stated my object is to provide a journal box by which I am enabled to compensate for the wear on account of the rotation of the shaft operative therethrough, whereby the shaft may be retained substantially true with relation to the parts with which it is connected.

Further particular objects are to provide a journal box incorporating in its construction a plurality of segmental bearing elements, having sleeves for their adjustment, with means whereby I am enabled to rotate the sleeves independent of the adjustment, and to provide for the adjustment of the sleeves longitudinally independent of the rotation.

A further object is to provide means, in connection with a journal box, for the more accurate adjustment of the surrounding bearing parts or segments, independent of each other in regard to their side margins; they being inclose in sleeves, which are adjustable longitudinally, the operation of the two sleeves being oppositely disposed with relation to each other in their longitudinal movements.

Another object is to provide a journal-box or the like having a continuous bearing surface from end to end and surrounding the shaft being supported, with means for avoiding the use of loose wedges, set-screws, and floater-rings, thereby avoiding a large proportion of the expense in installation and maintenance. And, finally, I provide a journal-box for shafting or the like, so con-

structed that it can be assembled and disassembled from either end or the top of the box without disturbing the alignment of the machinery.

Other particular objects and advantages will be brought out in the course of the following specification.

The construction of my invention, in two slightly dissimilar forms, is shown most clearly in the accompanying three sheets of drawings, in which

Figure 1 shows an end elevation of my modified construction, certain parts being broken away and appearing in section to show some of the interior construction and arrangements. Fig. 2 is a side elevation of the invention, partly in section at its lower portion, and as taken on line x-x of Fig. 1. Fig. 3 is a central section showing a detail view of one of the end plates, also showing the oil rings in position, and as taken on line y-y of Fig. 4. Fig. 4 shows an end view of parts of the invention illustrating the arrangement of the adjusting rings, the lower portion being in section, and showing manner of retaining the oil rings in position. Fig. 5 shows an enlarged side elevation, partly in section, illustrating the general arrangement of the essential elements of the invention, and showing the two half bearings or segments in connection with and inclosed by the two sleeves, which latter are connected by a circular band or ring. Fig. 6 is an end view, partly in section, of the parts shown in Fig. 5, and showing the manner of adjustment in relation to my preferred construction, and showing an adjusting wrench in connection therewith. Fig. 7 is a side elevation, partly in section, of the adjusting band or ring for connecting the sleeves. Fig. 8 is a detail view of a portion of said band or ring, showing the means for its rotation. Fig. 9 is a perspective view of the locking wedge, which is shown in operative position in Fig. 1. Fig. 10 is a detail view showing the application of my invention to a bearing formed of two segments instead of four. Fig. 11 is a side elevation of a portion of the inner end of one of said sleeves. Fig. 12 is a top plan view of my invention complete, showing the exterior arrangement thereof. Fig. 13 is a side elevation of my modified form, which contemplates the employment of four segmental bearings, showing one of the sleeves in position and with the other sleeve removed; and Fig. 14 is an end view

of the same. Fig. 15 is a side elevation of my preferred construction, which contemplates the employment of two segmental bearings, showing one of the sleeves in position; and Fig. 16 is an end view of the same. And Fig. 17 is an end view showing the opposite end of the parts shown in Fig. 4, but also showing the two segmental bearings as separated.

20 Similar reference characters denote like parts throughout the several views of the drawings.

In order that the construction and operation of the invention may be more fully understood I will now take up the description thereof in which I will describe the several parts and their relation one to the other as briefly and as compactly as I may.

In the drawings the letter A designates the 20 fixed portion or base member of the boxing, and the indice A' denotes the removable cap therefor, the latter being securable to the former by a plurality of bolts a. Formed centrally and horizontally through the base 25 and cap is a shaft aperture which is of greater diameter than is the shaft to be carried, the space formed by said aperture being equally divided in the base A and the cap A' as indicated. Formed through the center of the 30 cap A', at right angles to said horizontal aperture, is an oblong aperture which extends down and then opens convergently into said horizontal aperture, with its sides forming angles which are at right angles to said shaft aperture.

The letter M designates a key plug corresponding in general outline to said vertical aperture in the cap, see Figs. 1 and 9.

The indexes B and B' designate two sleeves 40 which are identical with each other but are oppositely disposed, each having a portion of its periphery threaded on its inner end portion with right and left threads, respectively, as indicated. Connecting said sleeves is a 45 band G provided with interior right and left threads to engage the threads of the respective sleeves, as shown in Fig. 5, by which if the band G be rotated in one direction the sleeves will be drawn towards each other, and 50 if rotated in the other direction the sleeves will be forced apart.

In the inner face of the sleeves B and B' I form two angular grooves or channels, E and E', respectively, as indicated, with their longitudinal angular inclination such as to give the proper movement to the segmental bearings presently referred to, said grooves E and E' being provided with parallel margins and spaced substantially opposite each other.

55 On either side of said grooves E—E' are formed two respective flat surfaces F and F', shown in Figs. 10 and 15, and they extend parallel through the sleeves B and B' as indicated. These angles E—E' and surfaces 60 F—F' are formed in the outer end portions of

the sleeves B—B' and extend inwardly a proper distance as desired.

The letter S denotes the shaft to be supported by my invention.

70 The sleeves B and B' have an interior diameter considerably larger than the shaft to be supported, and they are adapted to fit in and be free to move in said aperture.

Within the sleeves B and B' and surrounding the shaft S are arranged two bearing segments D and D', which are identical with each other, and they are spaced a proper distance apart to allow for taking up the wear caused by the rotation of the shaft S. Each of the segments D D' has an outwardly extending projection or rib, D¹ and D², extending longitudinally thereof and located opposite each other and whose sides are parallel with each other. The projections D¹ and D² are formed smaller at their extremities in order that the sleeves B and B' may be removed without displacing the segments D and D'. Said projections D¹ and D² are adapted to operate longitudinally in the respective grooves E and E', as indicated in 85 Figs. 6 and 10. Intermediate the ends of the segments D and D' is formed a series of apertures d to provide means for engaging a 90 wrench J or the like to rotate the segments as desired.

95 Formed around in the periphery of the band G are a number of equidistant cavities 3', in which may be engaged the wrench J' for rotating the band G. Formed through the band G are a plurality of apertures 4, located alternately between said cavities, through which may pass the prongs of the wrench J in order to engage the notches d of the segments D and D', as shown in Fig. 6. The wrenches J and J' may in fact be united 100 by a body or handle common to both, thereby forming one tool.

105 By turning the ring G a positive adjustment towards a center of axis may be provided on the segments D—D'. The sleeves 110 B—B' are of course free to move longitudinally as the band G is rotated. By turning the band G with the wrench J' it is evident that an equalizing opening and closing adjustment is obtained by the segments moving towards or from each other, and a longitudinal adjustment is obtained by the sleeves moving in an axial direction towards or from each other.

115 The open ends of the boxing are closed by 120 the caps I and I'. The cap I is secured by the screws 2, and the cap I' is secured by the screws 3. The caps I and I' should be cast in a manner to be broken into two equal sections as is indicated.

125 In the shaft opening are formed oblong grooves 12 to receive two semicircular or crescent-shaped oil-rings 13 and 14 which connect on opposite sides of the shaft. Said rings are held from turning by their exterior 130

forr, and are retained in engagement with the shaft S by the springs 15 and 16, as indicated in Fig. 4. The function of said oil-rings being to reduce to a minimum the escape of oil from the journal-box.

5. The key M will, normally, be retained in position by gravity, being seated neatly in the aperture formed therefor, but it may be secured if desired by a cap and nut, substantially as indicated in Figs. 1 and 2.

10. By the above description of the construction it will be notably apparent that I provide means whereby the shaft and the rotative parts of the boxing may be, at least, 15 partially submerged in oil, which may be injected into the boxing through the key aperture in the top of the cap A'.

15. It will be apparent from the above description that in rotting the sleeves B-B', by 20 means of the band G actuated by the wrench J, that it will also turn the bearing segments D-D' about the shaft S so that the position of the usual bearing surface will be changed with relation to the shaft. It will also be ob- 25 vious that a horizontal movement of the sleeves B-B', actuated by the wrench J' operating on the band G, will force the segments against the shaft S, or will relieve the close adjustment of the segments allowing 30 them to open out, according to the direction of the rotation of the band G.

35. In practice the base A is first placed in position, the cap A' being removed, and the shaft S suspended in the approximate position therefor. The sleeves B and B' are suspended loosely around the shaft on each side of the box, with the band G surrounding the shaft and hanging loosely within the boxing. I now bring the two bearing segments, D and D', to position around the shaft and within the casing, the band G having been previously encircling the segments and located centrally thereof, I then enter the threaded ends of the sleeves in the band, the threads being started by rotating the band. In this last position I have of course caused the said projections of the segments to enter the grooves formed on the inside of the sleeves. Now by rotating the band G 45 the sleeves may be drawn towards each other which will cause the segments to be forced towards each other adjusting them at the desired pressure against the shaft S. After said adjustment is obtained I then position 50 the cap A' and secure it to the base by the bolts a, as shown. The adjustment of the bearing segments in relation to the shaft having been previously obtained I now insert the key M in the aperture therefor in 55 the cap A', allowing the prongs of said key to pass through the corresponding apertures 4 in the band G with their points entering corresponding notches d in the segments D-D', as shown. By the above it is ap- 60 parent that the key M is caused to lock the

said parts together in their adjusted position, thereby forming the parts into a fixed unit.

In the event of the interior of the segments becoming worn, and the shaft having lost its center of axis within the boxing, I propose to compensate therefor as follows: I first remove the key M, and in place thereof insert the wrench J and then rotate together the segments D-D', the band G, and the sleeves B-B', bringing the worn portion of the segments to a new position. After the above I remove the wrench J and insert the wrench J' to engage the band G as in Fig. 8, and then rotate the band G to draw the sleeves B-B' towards each other until the segments D-D' are again in proper engagement with the shaft. I now remove the wrench J' and insert the key M, as before. By these operations I attain a new adjustment and, if desired, a new bearing surface, thereby compensating for the previous wear, thereby attaining the particular objects of my invention.

In Figs. 1, 2, 13 and 14 I have shown a modified form of construction, in which I have shown four segmental bearings in place of two, each segment being provided with means for its maintenance in position and for its guidance by the operation of the band G. Inside the sleeves are arranged the quarter bearings K, K¹, K² and K³, as shown in Fig. 1, same is provided with suitable clearance space therebetween which may be filled with a suitable substance for filtering and retaining the oil in suspension. Said quarter bearings are cut away and beveled adjacent their sides by lines located at substantially forty-five degrees inclination. Said quarter bearings are formed with reverse angles at their extreme ends to connect precisely with companion projections in the sleeves. Said sleeve projections are formed higher at their extreme ends to allow their removal. In rotating the ring G in one direction said quarter bearings all move centerward on parallel ways, or the reverse to open out. In other respects the modifications are substantially the same as the preferred construction. The operation of both forms is substantially the same, the modified form being designed mainly for extra heavy duty.

While I have herein shown and described the best means to me known at this time for the construction and operation of my invention, I desire that it be understood that various changes may be made in the details of construction thereof without departing from the spirit of the invention or sacrificing any of the advantages thereof.

What I claim and desire to secure by Letters Patent of the United States, is—

1. A journal-box comprising a casing, a shaft to be carried, a plurality of bearing seg-

- ments disposed about the shaft but separated from each other, sleeves surrounding the segments, a band connecting the sleeves by right and left threads, and means for locking the sleeves, the band, and the segments into a single unit after the same have been adjusted.
2. A journal-box comprising a casing, a shaft projecting therethrough, a pair of bearings disposed about the shaft and separated from each other, a pair of sleeves surrounding the bearings and adapted to be rotated, and a band connecting said sleeves for adjusting the sleeves longitudinally.
3. A journal-box comprising a plurality of segmental bearings disposed about a shaft and having clearance space between each other and rotatable concentric with the shaft, sleeves surrounding the segmental bearings, means for adjusting the sleeves longitudinally in relation to each other and to the shaft and independent of their rotation, and a casing for said parts having means for obtaining access to said parts without disturbing the adjustment.
4. A journal-box comprising a separable casing, rotatable sleeves carried in the casing, a band connecting the sleeves and threaded thereto with right and left threads thereby affording means whereby the rotation of the band causes endwise movement of the sleeves, a plurality of bearing segments located within the sleeves and rotative therewith and adapted to be forced towards each other when the sleeves are being drawn towards each other and to be separated when the sleeves are being forced apart, and means for locking the segmental bearings and the sleeves in adjusted position.
5. A journal-box comprising a casing, sleeves carried in the casing, a band connecting the sleeves with right and left threads thereby affording means whereby the rotation of the band causes endwise movement of the sleeves in directions opposite to each other, bearing segments located within the sleeves and adapted to be forced towards each other when the sleeves are being drawn towards each other and to be separated when the sleeves are being forced apart, and means for locking the segmental bearings and the sleeves in their adjusted positions.
6. A journal-box or the like comprising a separable casing, rotative sleeves disposed in the casing, a band connecting the sleeves and adapted to control the endwise movements thereof, bearings carried in the sleeves and adapted to be actuated thereby for varying their inside diameter, and means for securing said sleeves and bearings in adjusted position.
7. A journal-box having, in combination with a shaft, a separable casing, a pair of rotative sleeves disposed in the casing, a band connecting the sleeves and adapted to control the endwise movements thereof, bearings carried in the sleeves actuated thereby for varying their inside diameter, caps closing the ends of the casing, oil-rings carried in grooves formed therefor in the shaft opening, and springs for retaining said oil-rings in engagement with the shaft to prevent the escape of oil.
8. A journal-box comprising a two part separable casing, sleeves rotative in the casing, a band connecting the sleeves and adapted when turned to move the sleeves toward or from each other, bearing segments located in the sleeves and rotative therewith and adapted to carry a shaft therebetween, and means for preventing the escape of oil from around the shaft.
9. A journal-box comprising a base and a cap provided with a circular aperture formed therebetween which aperture is larger than the shaft to be carried by the journal-box, oppositely disposed sleeves fitting in said aperture and surrounding the shaft but separated therefrom, a band connecting the sleeves in the center of said aperture and adapted when rotated to move said sleeves apart or from each other, segmental bearings to contact with the shaft and located inside the sleeves and adapted to be controlled by said sleeves, means for locking the sleeves and the segmental bearings in adjusted position, and oil rings retained in contact with the shaft for preventing the escape of oil.

In testimony whereof I have hereunto subscribed my name in the presence of two subscribing witnesses,

FRANCIS ELLSWORTH BUXTON
